IOWA.

REINFORCED-CONCRETE RAILWAY-TIE.

1,322,985.

Specification of Letters Patent. Patented Nov. 25, 1919.

Application filed December 29, 1917. Serial No. 209,432.

To all whom it may concern:

Be it known that we, HARRY B. WIEBLER, WALTER T. WIEBLER, and GEORGE WIEBLER, residing at 520 Chestnut street, Fort Madison, county of Lee, and State of Iowa, all citizens of the United States, have invented new and useful Improvements in Reinforced-Concrete Railway-Ties, of which the following is a full, clear, concise, and exact 10 description, reference being had to the accompanying drawings, forming a part of this specification.

Our invention relates to improvements in reinforced concrete railway ties, and more particularly to that type in which heretofore metallic members having sloping sides extending transversely of the tie and embedded in the concrete body thereof have been provided for supporting the rails. The 15 drawbacks to such a construction are the limited length of the locking sides of said members, and the weakening of the concrete body of the tie resulting from the transverse cuts formed therein.

An object of our invention is to provide metallic rail supports so arranged and embedded in the concrete body of the tie as to utilize the ends as well as the lateral surfaces thereof for effecting a firm and secure 25 anchorage in said body.

A further object is to provide elongated hollow rail supports with downwardly diverging side walls extending longitudinally of the tie and embedded therein, whereby an 30 efficient anchorage is produced without detracting from the strength of the tie body.

And a further object is to interpose reinforced cushioning means between the rails and rail supports.

An embodiment of our invention is shown in the accompanying drawings forming a part of this specification and in which—

Figure 1 is a top plan view showing the complete tie excepting wooden rail seats and 40 spikes or screws employed therewith;

Fig. 2 is a central longitudinal section of the tie taken on line 2—2 of Fig. 1;

Fig. 3 is a top plan view of a rail support;

Fig. 4 is a transverse section taken through the tie on line 4—4 of Fig. 2;

Fig. 5 is a detail side elevation showing the central portion of a concrete reinforcing member employed in the tie;

Fig. 6 is a detail transverse section taken 55 through a rail support on line 6—6 of Fig. 3;

Fig. 7 is a side elevation of a rail support;

Fig. 8 is a top plan view of a wooden block 60 employed in a rail support;

Figs. 9 and 10 are, respectively, end and side elevations of said block;

Fig. 11 is a top plan view of a rail seat;

Fig. 12 is a transverse section of said rail 65 seat taken on line 12—12 of Fig. 11.

The preferred form of construction as shown in the drawings comprises a substantially rectangular concrete body 1 which is rigidly reinforced by means of longitudinally extending rods 2 and 3, the latter having V-shaped truss members 4 welded thereto, as shown in Figs. 2 and 3. An exceptionally strong and durable body is thus produced to serve as a foundation for hollow box-like rail supports 5 embedded in each end thereof. These supports are comparatively long and tapering in form so as to distribute the load imposed by the rails over a large area of the tie. The side walls 80 of supports 5 are dovetailed in body 1, or in other words they diverge downwardly to insure a firm anchorage in said body. Supports 5 are preferably of malleable iron and formed integral therewith are bearing plates 85 or chairs 6 which extend laterally over the side walls of said supports, as shown in Figs. 1, 3 and 6, so as to terminate in alignment with the sides of body 1. Slots 7 formed in bearing plates 6 are inclined to 90 the supported rails 8, in order to provide adjustment for rail securing screws 9 when rails having varying width of flanges are employed. Depending flanges 10 are provided on the longitudinal edges of bearing 95 plates 6 as shown in Fig. 6. These flanges are flush with the sides of body 1 and cooperate with the upper corners thereof for producing a rigid construction.

The large ends of the hollow rail supports 5 are provided with inwardly sloping walls 11 in order to facilitate the insertion of wooden blocks or wedges 12 which are shaped to conform to the interior of said supports, as shown in the several views. 100 The function of wedges 12 after being driven securely in place is to receive screws 9, there being holes 13 for the reception of

said screws, as shown in Fig. 8. Due to the sloping sides of wedges 12 and the fit thereof to the walls of supports 5, it is not necessary that the upper wedge surfaces come in contact with plates 6 to resist the upward pull of screws 9. In fact a clearance exists between said plates and wedges, as will be seen by reference to Fig. 2. This wedge construction forms an important part of our invention, since vibration is absorbed thereby, and replacement or repair of the wedges is rendered possible when necessary. A wedge may be readily removed by inserting a pry between an end wall of a support 5 and the small end of the wedge, and forcing the wedge toward the large end of said support after removal of screws 9.

Rail seats 13', which are preferably formed of wood or other cushioning material, are provided on bearing plates 6, there being a central rib 14 on each plate which is arranged in alinement with rails 8, as shown in Fig. 3. Each seat 13' is provided with a groove 15 formed to fit rib 14, which construction facilitates positioning of the seats when assembling the parts, and cooperates with screws 9 in resisting lateral displacement of the rails. The grain of the wood seats 13' runs transversely of the rails resting thereon, and in order to prevent undue crushing or splitting of said seats, wires 18 are wrapped thereon, as shown in Fig. 11. Notches 17 providing clearance for screws 9 are provided in seats 13'.

After rails 8 have been secured by screwing screws 9 into wedges 12, the spaces between the large end of said wedges and the sloping walls 11 may be filled with a suitable material, such as crushed rock, as indicated in Fig. 2. Or, if desired, a waterproofing material, such as concrete or asphalt, may be employed which would resist corrosion of the metal parts.

It will be noted that the lateral extensions of bearing plates 6 rest directly on the concrete of body 2, and that the area of contact is such as to adequately support these plates when subjected to the heaviest loads.

It will also be seen that the small ends of rail supports 5 are disposed toward each other with the bearing or diverging ends thereof adjacent the ends of the tie, the consequence being that weakening of the tie, if any, by the insertion of said supports is reduced to a minimum.

While we have illustrated and described the preferred form of construction for carrying our invention into effect, there might be variations and modifications thereof without departing from the spirit of our invention. We, therefore, do not wish to be limited to the precise details of construction set forth, but desire to avail ourselves of such variations and modifications as come within the scope of the appended claims.

We claim as new and desire to secure by Letters Patent of the United States:

1. A railway tie comprising a rectangular concrete body with substantially unbroken side walls, hollow metal rail supports inserted in said body and provided with downwardly diverging side walls, a bearing plate formed integral with each support and resting on said body, and wood blocks secured in said supports under the bearing plates thereof for the reception of rail securing screws.

2. A railway tie comprising a concrete body, elongated tapering hollow rail supports inserted in the top of said body and extending longitudinally thereof, downwardly diverging side walls in said supports forming an anchoring means in said body, bearing plates formed integral with said supports and having portions thereof resting on said body, wedges shaped to conform with the interior of said supports and disposed under said plates, and means for connecting rails with said wedges.

3. A railway tie comprising a reinforced concrete body having a flat upper surface and substantially unbroken side walls, hollow metallic rail supports inserted in said body so as to be flush with said surface, longitudinally tapering and downwardly diverging side walls in said supports, a bearing plate cast integral with each support and having extensions resting on said body, a removable wooden wedge shaped to conform to the side walls of each support and disposed under the bearing plate thereof, there being slots in each plate, a rail above each support, and screws passing through said slots and connecting the rail flanges with said wedges.

4. A railway tie comprising a reinforced concrete body, hollow metallic rail supports inserted in the ends of said body, there being horizontal bottom walls and downwardly diverging side walls tapering toward each other in said supports, a bearing plate extending across the top of each support and having extensions resting on said body, a removable wedge in each support shaped to conform to the side walls thereof and disposed under said plate, there being a sloping end wall in each support to facilitate the insertion of said wedges, a reinforced wood rail seat resting on each plate, and screws for connecting rail flanges with said wedges.

5. A railway tie comprising a reinforced concrete body, a hollow metallic rail support inserted at each end of said body, downwardly diverging side walls in each support which taper toward each other, a bearing plate cast integral with each rail support and extending across the top thereof with ends resting on said body, depending flanges at the ends of said plates conforming to cor-

ners of said body, detachable wooden wedges conforming to said side walls and disposed under said plates, there being inclined slots in said plates, rail seats on said plates, and 5 rail securing screws passing through said slots into said wedges.

6. A railway tie comprising a concrete cross member, a metallic box member embedded in said concrete member, and a 10 wooden block secured in said metallic box in position to lie beneath the lower flange of the rail and extend beyond said flange on both sides, whereby fastening members may be inserted in said wooden block on 15 both sides of said flange, the side walls of said box tapering upwardly and inwardly and said wooden block snugly fitting against said walls.

7. A railway tie comprising a concrete 20 cross member, a metallic box member embedded in said concrete member, and a wooden block secured in said metallic box in position to lie beneath the lower flange of the rail and extend beyond said flange on 25 both sides, whereby fastening members may

be inserted in said wooden block on both sides of said flange, the side walls of said box converging and the side faces of said wooden block converging also, whereby the wooden block may be wedged into the box. 30

8. A railway tie comprising a concrete cross member, a metallic box member embedded in said concrete member, and a wooden block secured in said metallic box in position to lie beneath the lower flange of 35 the rail and extend beyond said flange on both sides, whereby fastening members may be inserted in said wooden block on both sides of said flange, the side walls of said box converging upwardly and also converging 40 longitudinally, and the side faces of said wooden block also converging upwardly and longitudinally, whereby said block may be wedged tightly into said box and will be firmly held in position. 45

In witness whereof, we have hereunto subscribed our names.

HARRY B. WIEBLER.

WALTER T. WIEBLER.

GEORGE WIEBLER.
